(No Model.)

W. HOHNSTEIN.
METAL FOLDING RULE.

No. 439,511.

Patented Oct. 28, 1890.

Inventor:
William Hohnstein.

By Knight Bros.

actg's.

UNITED STATES PATENT OFFICE.

WILLIAM HOHNSTEIN, OF ST. LOUIS, MISSOURI.

METAL FOLDING RULE.

SPECIFICATION forming part of Letters Patent No. 439,511, dated October 28, 1890.

Application filed February 21, 1890. Serial No. 341,298. (No model.)

To all whom it may concern:

Be it known that I, WILLIAM HOHNSTEIN, of the city of St. Louis, in the State of Mis-

souri, have invented a certain new and useful

5 Improvement in Metal Folding Rules, of which the following is a full, clear, and exact description, reference being had to the accompanying drawings, forming part of this specification.

10 This invention relates to a solid-metal folding rule in which the major hinge is provided with two pairs of dual center hinge-plates that conjointly fit to the outside of their respective sections, to which they are secured, and hav-

15 ing minor hinges integral with the quarter-junctions of said sections, and which rule is provided with parallel dual clutch-lugs secured to certain sections of said rule-plates, and that clutch their corresponding sections when

20 folded and hold them to their conjoint registered positions within the embrace of said lugs; and the invention consists in features of novelty hereinafter fully described, and pointed out in the claims.

25 Figure I is a side perspective of the rule closed. Fig. II is a like view of the rule open. Fig. III is an enlarged vertical section taken on line III III, Fig. I, and shows the corresponding quarter-sections of the rule-

30 plate held in their folded registering position by the dual lugs secured to one quarter-section, and that embrace its corresponding folded section. Fig. IV is a detail perspective view of the major hinge, showing the parts disassembled.

35 Referring to the drawings, 1 represents the folding quarter-sections of the rule, on which is inscribed the graduated measurement-scale 2 and indicating-figures 3 marked thereon, 40 which rule in all its parts is preferably made of brass, but may be of any other suitable metal.

45 4 represent dual plates of the major or center hinge, and 5 are circular projections from said plates.

50 6 are dual corresponding surface plates to the hinge-plates above mentioned, and whose concave recessed edges 7 fit to the convex edges 8 of the projections 5 of said plates.

55 These hinge-plates are respectively secured to the outsides of said sections of the rule, preferably by rivets 9, that are seated and

riveted in the perforations 10 in said plates and rule-sections; but they may be secured by brazing or by any suitable means.

55

11 represents a circular projection from the hinge end of the rule quarter-section, to which are attached the plates 6, and which projection registers and works within the circular projections 5 of the hinge-plates 4 and within 60 the concave recess 12 of its conjoint quarter rule-section. The pivot-pin 13 is seated in the center bearings 14 in the circular projections 5 of the hinge-plates 4, and the like corresponding projections of its conjoint rule- 65 section pivotally secures together the members of the major hinge.

15 represent the minor or quarter hinges which pivotally secure together the middle quarter-sections of the rule to their terminal 70 quarter-sections. The alternating loops 16, which are integral with the respective quarter-sections that they couple together, are pivotally connected by the hinge-pins 17.

19 represent the dual parallel clutch-lugs, 75 which are secured to certain of the corresponding quarter-sections of the rule, preferably by rivets 20, that are seated and riveted in the perforations 21 in said lugs and in said sections of the rule; but said lugs may be secured to said quarter-sections by brazing or by any other suitable means.

80 Now it will be seen that this solid-metal rule will fold into a more compact compass than either a wooden or ivory rule, which to 85 have the requisite strength must have largely more material in it, or of a tubular metal rule, which is also too bulky for pocket use, for which folding rules are generally intended.

It will also be seen that as the brass or other 90 metal plate of which the quarter-sections of the rule are constructed can be and preferably is of not more, and may be less, than a sixteenth of an inch in thickness, so as to fold into a mere compact form for a pocket-rule, 95 it became necessary that some other means of clamping together the quarter-sections of the rule should be devised, as the plate of which they are constructed is too thin for the insertion of the usual pointed dowel-pin 100 in one quarter-section and the socket-hole in the corresponding section in which said dowel-pin registers, when the rule is folded. Besides that, the said pointed dowel-pins have

always been objectionable, scratching and marking up the corresponding quarter-sections of the rule with which they engage, and, worse yet, having the same effect on the hands of the mechanic or other person who uses said rule. To avoid all these difficulties and at the same time more securely hold the quarter-sections of the rule together, I have devised the dual thin clutch-lugs 19, which 5 embrace the corresponding sections instead of puncturing them with dowel-pins.

While this pocket-rule is convenient and useful for all mechanics and others who carry a rule, it is especially well adapted for the 10 use of master mechanics and foremen in machine-shops, who require a light and handy metal pocket-rule always at hand and easily handled for testing the hot as well as cold metal work that is being produced in the 15 shops.

I have shown and described the minor 20 hinges that connect the terminal quarter-sections to the center sections integral with said sections, yet, although said construction is preferred, I do not confine myself thereto, for 25 separate hinges may, if desired, be riveted or otherwise secured to said quarter-section at said pivot-joints without departing from the essential features of the invention.

30 I claim as my invention—

1. A solid-metal folding rule constructed 35 with a section formed with a concave recess 12 at its inner end and provided with two outside hinge-plates 4, each having a circular projection 5 and a pivot-hole 14, a section formed with a circular projection 11, integral there-

with, at its inner end fitting said recess 12, having a pivot-hole and provided with two outside hinge-plates 6, each having a concave recess 7 fitting a projection 5, and a pivot-pin 40 13, by which the three circular projections are secured together for hinging the sections together, substantially as described.

2. A solid-metal folding rule constructed 45 with sections, major hinges connecting the sections, and a pair of clutch-lugs 19, secured to the inner edge of one section and embracing the inner edge of the opposite section, substantially as described.

3. A solid-metal folding rule constructed 50 with four sections formed with minor hinges integral therewith, a pair of clutch-lugs 19, secured to the inner edge of two of the sections and embracing the inner edge of the opposite sections, one of the inner sections being formed 55 with a concave recess 12 at its inner end and provided with two outside hinge-plates 4, each having a circular projection 5 and a pivot-hole 14, and the other inner section being formed with a circular projection 11, integral therewith, at its inner end fitting said recess 12, having a pivot-hole and provided with two outside plates 6, each having a concave recess 7 fitting projection 5, a hinge-pin 17, connecting the minor hinges, and a pivot-pin 13, by which 60 the three circular projections are secured together, for hinging the inner sections together, substantially as described.

WILLIAM HOHNSTEIN.
